His Attorney.

UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

X-RAY APPARATUS.

Original application filed July 9, 1920, Serial No. 395,088. Divided and this application filed April 26, 1923. Serial No. 634,864.

To all whom it may concern:

Be it known that I, WILLIAM D. COOLIDGE, a citizen of the United States, residing at Schenectady, in the county of Schenectady, State of New York, have invented certain new and useful Improvements in X-Ray Apparatus (division of my prior application Serial No. 395,088, filed July 9, 1920), of which the following is a specification.

10 The present invention comprises an X-ray apparatus which is particularly suited for radiography although it is not limited in its use to this particular purpose.

When utilizing X-rays for diagnostic purposes, it is particularly desirable to secure a constant radiographic effect for a given setting so that for comparison purposes the resulting radiographs may be of equal density. For example, for a constant impressed voltage and X-ray producing current, and for a given subject, an X-ray tube operating by electron conduction substantially independently of gaseous ionization, will always produce a radiograph of the same density for a given exposure. As explained by Prof. J. S. Shearer in the American Journal of Roentgenology, Vol. 3 (1916), page 300, the radiographic effect may be expressed as follows in terms of current (I), time (T), voltage (V), and distance (D).

$$R.E. = \frac{IT \times V^2}{D^2}$$

35 The distance between the X-ray source and the photographic plate or film can readily be maintained constant.

It would appear in view of this that with a given patient, a doctor or dentist could 40 always get the same sort of radiograph by the use of a simple time switch. As a matter of fact, this ideal condition is obtainable only in a laboratory under carefully controlled conditions. Ordinarily the available current supply is extremely variable in voltage, and consequently a time switch alone is insufficient to give a substantially 45 constant radiographic effect.

In accordance with my invention, I have 50 provided an X-ray apparatus constructed to give a substantially constant radiographic effect even with a variable supply of voltage. The novel structural features of my inven-

tion will be pointed out with particularity in the appended claims.

55 My invention will be described in detail in the following specification taken in connection with the accompanying drawings in which Fig. 1 illustrates diagrammatically a system embodying my invention; Fig. 2 is 60 a diagram of a set of curves showing the currents in the transformer furnishing current for heating the cathode of the X-ray tube; and Fig. 3 illustrates diagrammatically one form of cathode heating transformer suitable for use in my improved apparatus.

65 The system shown in Fig. 1 contains an X-ray tube 1 of the hot cathode type supplied with heating currents from a special 70 transforming apparatus 3 which is designed to give a heating effect which varies inversely with the supply voltage. In the construction illustrated in Fig. 1 and Fig. 3, the transformer 3 is provided with two primary windings 4 and 5.

75 As illustrated in Fig. 3, the primary windings 4 and 5 are located on separate cores 6 and 7. The core 6 is rectangular and is so constructed as to provide a highly saturated magnetic circuit for its primary winding 4 and the secondary winding 8 with normal voltage on the apparatus. The arrangement of the core and windings illustrated provides for an appreciable magnetic 80 leakage between the windings. The section 5 of the primary winding is wound on an open magnetic core 7 with an auxiliary secondary winding 9. The core 7 is so constructed as to operate far below saturation. 85

90 The change of voltage at the terminals of the auxiliary secondary winding 9 takes place at a fairly low rate as the primary voltage changes. The core 7 has been shown as an open magnetic core to illustrate this 95 feature. The two primary transformer windings 4 and 5 are connected in series with each other by conductors 10 and 11 to the source of energy represented by the mains 12 and 13. The main secondary winding 8 and the auxiliary secondary winding 9 are also connected in series, but are 100 so connected that the induced electromotive forces oppose each other. The conductors 14 and 15 leading from the terminals of 105 these windings are connected in series with

an adjustable resistance 16 (Fig. 1), to the primary of a transformer 17, the secondary of which is connected by conductors 18, 19, to the terminals of the cathode 2 of the 5 X-ray tube. In some cases the transformer 17 may be omitted.

- The sum of the magnetic fluxes in the saturated and unsaturated magnetic circuit varies in proportion to the voltage variation of the supply circuit 12, 13, but the fluxes in the two secondary windings vary at different rates. By properly proportioning the secondary windings, which are connected in opposition, the sum of the voltage 10 in the conductors 14, 15 may be made to decrease as the voltage impressed on the primary windings 4, 5 increases, in such measure as to produce a substantially constant radiographic effect.
- 15 The operation of the filament lighting transformer will be more clearly understood from the diagram of electromotive forces shown in Fig. 2. The voltages induced in the main and auxiliary secondary windings 20 are measured along the vertical line 22 and the currents in the primary windings are measured along the horizontal line 23. Since the core 6 is highly saturated at 25 normal voltages the total electromotive force induced in the main secondary winding 8 varies with the variations of primary current in the general manner represented by the curve 24, 25. A change of the electromotive force in the auxiliary secondary 30 winding 9 is indicated by the curve 26. This curve 26 is drawn below the horizontal zero line to indicate that this electromotive force opposes the electromotive force of the curve 24, 25, the main and auxiliary secondary 35 windings 8, 9 being connected in opposition. The resultant secondary voltages across the conductors 14 and 15 therefore may be represented by the curve 27, 28. This resultant curve rises rapidly at first over the portion 40 27, and then bends downwardly. As the current in the primary winding increases with an increase of impressed electromotive force, the voltage in the conductors 14 and 15 decreases.
- 45 The cathode 2 and anode 20 of the X-ray tube are connected by conductors 63, 64 to a high potential transformer 65, the primary of which is connected by conductors 66, 67 to the mains 12, 13. In series with the 50 primary of the transformer 65 is a time switch 68, which has been diagrammatically shown in the drawings, and may be of any preferred construction. When the time switch is set to give an exposure of given 55 length, should the voltage in the main conductors 12, 13 vary, for example, should it increase, thereby increasing the voltage across the terminals of the X-ray tube, and consequently increasing the penetrability of 60 the X-rays, then by the action of the de-

scribed construction in the filament lighting transformer, the temperature of the cathode decreases at such rate that the resulting radiographic effect for the given exposure is substantially constant over a working 70 range.

Conversely, a decrease of voltage of the supply source will result in an increase of voltage of the filament lighting current, increasing the temperature of the cathode and thereby increasing the milliamperage of the current through the tube, and thus compensating for the decrease of impressed voltage so as to give over a working range a substantially constant radiographic effect. 75 Instead of varying the current through the tube the other member of the current-time factor may be varied, while the current is maintained constant. This modification is claimed in my prior application of which 80 the present application is a division.

In the system herein described the time interval and the distance from tube to film are maintained constant. When the impressed voltage varies the space current 90 through the tube, over a working range, will vary inversely substantially as the square of the voltage impressed across the tube. As indicated by the equation given above, 95 this variation of current maintains the radiographic effect substantially constant. As a slight change in cathode heating current will produce a relatively great change in electron emission and as this change of emission will vary with the tube conditions, the required voltage variation of cathode heating current for a given set of conditions to produce the current variation required to give a constant radiographic effect must be determined by trial and the transformer 100 ratios adjusted accordingly.

It is customary to operate the cathode of an X-ray tube of the Coolidge type at the saturation value of electron emission. In other words, the impressed voltage is sufficiently high to carry away substantially all of the electrons emitted by the cathode. As the electron emission with varying cathode 110 temperature varies at a high rate according to the well-known Richardson equation 115

$$I = aT^{\frac{3}{2}}e^{-\frac{b}{T}}$$

(I being electron current, T cathode temperature, a and b constants and e a logarithmic base), the size of the transformer core, ampere turns and other transformer characteristics can be chosen in accordance with the well-known principles of transformer design to cause the electron emission to vary inversely with the square of the supply voltage. The space current value necessarily must vary at the same rate when the cathode is operated at saturation value of electron emission.

What I claim as new and desire to secure by Letters Patent of the United States, is:— 120 125 130

1. The method of obtaining a predetermined output of X-rays from an X-ray tube which is energized by a current of variable voltage which consists in regulating the electron emission at the cathode substantially inversely with the square of the voltage.
2. The method of obtaining an X-ray output of predetermined radiographic effect from an X-ray device energized by a source of current of variable voltage which consists in timing the interval of operation of said X-ray device and regulating the current transmitted by said device substantially inversely with departure of voltage from a predetermined value to produce a constant radiographic effect.
3. An apparatus for operating an X-ray tube with current of variable voltage which consists of a main transformer adapted for connection to said tube and constructed to deliver current having a voltage proportional to the voltage of said source, and means for regulating the electron emission of the cathode of said tube inversely with respect to voltage variations of operating current supplied to said transformer in such measure as to produce a substantially constant radiographic effect.
4. An X-ray apparatus adapted for operation from a source of current of variable voltage comprising an X-ray device, electric connections for operating said device from said source, a time switch in circuit with said device, and means for regulating the current in said device substantially inversely in response to voltage variations of operating current, thereby producing an X-ray output of substantially constant radiographic effect for a given time interval of operation.
5. An X-ray apparatus comprising an X-ray tube, a source of current subject to variations of voltage connected to generate X-rays in said tube, means for heating the cathode of said tube by a current varying substantially inversely in voltage with the current which generates X-rays.
6. An X-ray apparatus adapted for operation from a source of current subject to voltage variations, comprising an X-ray tube having a cathode adapted to operate at incandescence, a transformer connected to generate X-rays in said tube and adapted to be supplied by said source, and means for heating the cathode of said tube by current varying in voltage substantially inversely with the operating voltage of said transformer in such measure as to produce an X-ray output of substantially constant radiographic effect.
7. An X-ray apparatus comprising an

X-ray tube, a main transformer connected to generate X-rays in said tube, an auxiliary transformer connected to heat the cathode of said tube, and a common supply circuit carrying current of variable voltage, said auxiliary transformer being constructed to deliver current varying inversely in voltage with variations of voltage of said supply circuit.

8. An X-ray apparatus comprising an X-ray tube, an energizing source operatively connected to generate X-rays therein, a transforming apparatus comprising a plurality of primary windings connected in series to said source, corresponding secondary windings connected in opposition, a core for one of said sets of primary and secondary windings constructed to be highly saturated, a second core for another set of said windings constructed to operate below saturation, said cores being constructed to have their fluxes vary at different rates in proportion to voltage variations in the primary windings, and said cores and secondary windings being proportioned to deliver a current varying in voltage inversely in proportion to the voltage of said source, and electric connections between said secondary windings and the cathode of said X-ray tube.

9. An X-ray apparatus comprising the combination of a source of alternating current subject to variations of potential, an X-ray tube having a cathode adapted to be heated to incandescence by passage of current, means for operating said tube by current derived from said source, and transforming means connected to said cathode comprising primary windings connected in series, separate cores therefor and corresponding secondary windings connected in opposition arranged and constructed to deliver a heating current for said cathode varying in voltage in such measure, as to vary the cathode temperature in response to voltage variations of said source of alternating current, that the radiographic effect of X-rays generated by said tube for a given time interval is substantially constant when the supply voltage varies.

10. An X-ray apparatus adapted to be operated with current of variable voltage comprising an X-ray device, electric connections for operating said device from said source, and means for regulating the current in said device substantially inversely in response to the square of voltage variations of operating current.

In witness whereof, I have hereunto set my hand this 25th day of April, 1928.

WILLIAM D. COOLIDGE.
